UNITED STATES PATENT OFFICE

GARNET P. GRANT, OF LONG ISLAND CITY, NEW YORK, ASSIGNOR TO AUTO-SALES CORPORATION, OF LONG ISLAND CITY, NEW YORK, A CORPORATION OF NEW YORK

ROCKABLE DELIVERY DEVICE FOR VENDING MACHINES

Application filed December 20, 1928. Serial No. 327,253.

This invention relates to a rockable delivery device for vending machines.

As is well known in the art of vending machines commodities are placed in a chute, one package on top of another. Ordinarily a coin release device of common construction is used whereby on the insertion of a coin a rotative or rockable member is released and the commodity is pushed from the bottom 10 of a chute and permitted to drop so that the purchaser may take the same from an ordinary form of casing.

Ordinarily, when by a coin release mechanism a movable member is pushed towards the rear end of a casing a package of the commodity to be vended is forced towards the rear wall of the casing. The ordinary course of the package is graphically shown in Figure 1 of the drawing.

One of the objects of the invention is to 20 catch the packaged commodity on a swinging plate so that the rear edge is elevated and so that the front edge, by the force of gravity, is dropped forward and downward so that it is freely released to be picked up by the purchaser.

A further object of the invention is to provide a pivotally supported plate which will contact with the back edge of a package of 30 commodity so as to prevent the turning of the package with the effect of delivering the package with its front edge towards the front wall of the casing containing the commodity and with the further effect of preventing the 35 package becoming jammed in delivery.

The invention consists of the construction, combination and arrangement of parts as herein illustrated, described and claimed.

In the accompanying drawing forming 40 part hereof is illustrated one form of embodiment of the invention in which drawing similar reference characters designate corresponding parts and in which:

Figure 1 is a vertical section through a 45 common type of vending machine showing the application of the invention;

Figure 2 is a horizontal section taken approximately on line 2-2 of Figure 1, looking in the direction indicated by the arrows; 50 and,

Figure 3 is a perspective of a commodity containing chute showing the application of the invention thereto.

Referring to the drawing 4 designates a common form of casing known in the art, in 55 which is disposed a package chute 5 arranged to receive packages 6 of commodities of any character.

At one side of the package chute 5 is arranged an ejecting element 7 constructed to 60 force the bottom package 6 through the rear opening 8 of the package chute 5. At the back of the casing 4 is arranged the usual curved wall 9 for the purpose of directing the packages 6 towards the front of the cas- 65 ing 4. For the purposes of this patent the foregoing arrangement of elements may be considered as common knowledge.

Arranged on and secured to the side walls of the chute 5 are ears 10 placed to support a 70 transverse rod 11. The rod 11 may be pivotally supported on the ears 10 or a plate 12 may be pivotally supported on the rod 11. The plate 12 is provided with an offset portion 13 having thereon an angular face 14 75 which terminates in a lower angular lip 15.

The pusher or ejecting element 7 and the package chute 5 are supported upon an ordinary supporting platform 16, all contained within the casing 4. 80

A suitable projecting bracket 17 is secured to the chute 5 at any convenient point to limit the movement forward of the rockable directing element 12, so as to prevent the rockable element 12 from swinging so far forward to 85 occlude the movement of the packages 6 as they are forced rearwardly as shown in Figure 1.

The cycle of operation of the machine is as follows: The ejecting element 7 being actuated rearwardly or to the right hand of Figure 1 strikes the corresponding lowermost package 6 and forces it to the dotted line position, rocking the plate 12 rearwardly to the dotted line position. The package 6 at its 90 rearmost edge then rests on the angular lip 15 and by gravity is dropped to the position of the second dotted line position of Figure 1 so that it is directed by the curved plate 9 towards the front end of the casing 4. 100

Having thus fully described the invention what is claimed as new and desired to be secured by Letters Patent is:

In a vending machine, the combination comprising a vertical delivery chute containing a stack of articles to be vended, means for ejecting the lowermost article of the stack laterally from the chute, a rockable member pivoted so as to swing toward and from the chute, a lip carried on the lower end of the member at a position below the chute and an abutment for maintaining the rockable member with its lip out of vertical alignment with the chute, the arrangement being such that one end of the article during its ejection from the stack is carried by the lip of the rockable member.

In testimony whereof I affix my signature.
GARNET P. GRANT.
